UNITED STATES PATENT OFFICE.

JOHN E. JOHNSON, OF DE KALB, ILLINOIS, ASSIGNOR TO JOHNSON FAN CO., OF CHICAGO, ILLINOIS, A COPARTNERSHIP COMPOSED OF C. O. NELSON, JOHN E. JOHNSON, AND ERNEST E. JOHNSON.

DISCONNECTIBLE FAN FOR AUTOMOBILES.

1,427,687.

Specification of Letters Patent. Patented Aug. 29, 1922.

Application filed October 8, 1920. Serial No. 415,682.

To all whom it may concern:

Be it known that I, JOHN E. JOHNSON, citizen of the United States, residing at De Kalb, Illinois, have invented certain new and useful Improvements in a Disconnectible Fan for Automobile; and I do hereby declare the following to be a full, clear, and exact description of the invention, such as will enable others skilled in the art to which it appertains to make and use the same.

My invention relates to mechanism for forcing air through the radiators of automobiles so as to cool these radiators and maintain them in proper operative condition. Heretofore, it has been customary to provide suction fans for this purpose and to have the same continuously connected to the engine, so that they will be operative at all times when the engine is running unless the fan belt is manually detached. In practice, such a continuously operating fan is highly desirable in warm weather, but is undesirable in cold weather and in certain seasons is only intermittently to be desired. For example, on a chilly day, the use of the fan when the engine is first started will tend to cool the engine unduly, thereby seriously interfering with its efficiency, although the operation of the fan may be advisable after the engine has been running for a length of time sufficient to cause these metal casing portions to become well heated. Consequently, the continuously operative driving connection between the air propelling fan and the engine as heretofore employed is undesirable under such conditions, and the same applies also at times where there are decided changes in temperature, as for example when a cool night follows a hot day.

My invention aims to overcome this objection to be continuous operation of the radiator-cooling fan by providing a fan which can readily be controlled as to its operation by the driver of the automobile, for which purpose I preferably aim to provide a simple construction which can readily be substituted for the ordinary fan on a standard automobile and which can be controlled in operation by the driver of the automobile without having the latter leave this seat. While the appliance of my invention may be adapted with substantially equal facility and substantially equal advantages to widely varying types of automobiles, it is particu-

larly suited for automobiles of the Ford type and is therefore illustrated in such an embodiment in the accompanying drawings, although I do not wish to be limited to this particular application.

In the drawings, Fig. 1 is a fragmentary side elevation of the engine and adjacent parts of a Ford automobile, showing my invention as it appears in use when the fan is running.

Fig. 2 is an enlarged central and longitudinal section through the disconnectible driving arrangement for the fan.

In the embodiment of the drawings, the fan 1 is freely rotatable on a shaft 2 which is fast on the usual fan-supporting standard 3 located immediately in front of the engine 4. Adjacent to this standard, the shaft 2 has a pulley 5 which also is freely rotatable on the shaft 2 and which is driven through the usual fan belt 6 from the shaft 7 of the engine. The pulley 5 has fast upon it a bushing 7 equipped with chuck jaws 8 which normally interlock with jaws 9 on a collar 10, the latter collar being integral with the hub to which the blades of the fan 1 are fastened. The chuck jaws 8 and 9 are normally forced into interlocking relation with each other by a spring 11 interposed between the hub 10 and the washer 12 which is kept from sliding towards the free end of the shaft by any suitable means, as for example by bearing against a spring cotter 13 which extends through a transverse bore in the shaft 2 adjacent to the free end of the latter. The hub 10 has a shoulder formation 14 facing the pulley 5, and this shoulder 14 is continuously engaged by the tips of the prongs of a fork 15 which is at the lower end of a rocking lever 16. This lever is pivoted on a bracket 17 bolted to the engine (desirably by one of the same bolts 18 which connect the top water connection to the casing of the engine) and the upper end of the rocking lever 16 is connected by a rod 19 with a handle 20 extending through a perforation 21 in the dash board 21 and having a ring 22 on the driver's side of the dash board, so that the driver of the automobile can readily pull the rod 19 toward himself by grasping this ring.

In ordinary operation the mechanism appears as shown in Fig. 1 with the spring 11 holding the clutch jaws interlocked, so that

the fan rotates in unison with the pulley 5 and consequently exerts its cooling effect. However, by pulling the ring of the handle 22 towards him, the driver of the automobile 5 can readily rock the lever 16 so that the fork tips 15 will slide the hub 10 of the fan towards the right in Fig. 1, thereby moving the clutch jaws 8 and 9 out of engagement or into the disconnected position of Fig. 2. 10 Then the driver can latch the parts in this position by letting the forwardly directed shoulder 23 on the latching member 20 snap into engagement with the rear of the dash board. By so doing, he can hold the fan out 15 of operation for any desired length of time, the pulley 5 being prevented from crawling along the shaft 2 by the engagement of a forwardly directed shoulder 24 in the bore of this pulley with a corresponding rearwardly 20 directed shoulder on the shaft 2, as shown in Fig. 2.

With the parts thus arranged, it will be evident that the operation of the fan is entirely under the control of the driver of the 25 vehicle, so that he can connect or disconnect the same instantly, thereby securing the full benefit of the fan action whenever it is desirable to profit by the cooling action of the forcibly propelled air, but without suffering 30 at any time by a continued operation of the fan when this is not desirable. However, while I have heretofore illustrated and described my invention in a highly desirable embodiment suitable for use on a particular 35 type of automobile and including certain simple means for supporting the rocking lever and for effecting the latching and unlatching, I do not wish to be limited to these or other details here disclosed. Obviously, 40 numerous alterations in both the construction and arrangement could be made without departing from the spirit of my invention or from the appended claims. So also, I do not wish to be limited to the use of 45 my invention in the particular location as here illustrated with respect to the automobile engine, nor in connection with any particular make of vehicle.

I claim as my invention:

50 1. In a combination with the bolted top water connection of the engine casing and the radiator cooling fan and hub of an auto-

mobile, a stationary shaft on which the fan hub is freely rotatable, an engine driven pulley freely rotatable on the shaft, the fan hub and pulley having normally interlocked, 55 clutch faces, a spring on the outer end of the shaft engaging the fan hub for normally holding the clutch faces interlocked, a bracket apertured to receive said bolt of the water connection for affixing same to the engine casing and having a depending part, a lever pivoted between its ends to the depending part of the bracket and having its lower end arranged in front of the pulley and 60 straddling the fan hub for sliding same on the shaft, the upper end of the lever extending above the water connection, and means connected to the upper end of the lever and to the dashboard for operating the 65 lever.

2. In combination with the radiator cooling fan and hub of an automobile, a stationary shaft on which the fan hub is freely rotatable, an engine driven pulley freely rotatable on the shaft, the fan hub and pulley having normally clutched clutch faces, a 75 spring on the shaft for normally holding the clutch faces in clutched relation, a bracket, means to secure the bracket to the engine casing, a lever pivoted between its ends to the bracket and having one end engaged with the fan hub so as to slide the latter on the shaft, and means to operate the lever connected to the opposite end thereof. 80

3. In a combination with the bolted top water connection of the engine casing and the radiator cooling fan and hub of an automobile, a stationary shaft on which the fan hub is freely rotatable, an engine driven pulley freely rotatable on the shaft, a fan 90 hub and pulley having normally interlocked clutch faces, a spring on the outer end of the shaft engaging the fan hub for normally holding the clutch faces interlocked, a bracket apertured to receive said bolt of the water connection for affixing same to the engine casing, means on the bracket connected 95 to the fan hub for sliding same on the shaft and means to actuate said last named 100 means.

Signed at De Kalb, Illinois, Sept. 24th, 1920,

JOHN E. JOHNSON.
